UNITED STATES PATENT OFFICE.

LEWIN A. MISKELL, OF NELSONVILLE, OHIO.

SEAT.

1,050,676.

Specification of Letters Patent. Patented Jan. 14, 1913.

Application filed September 21, 1912. Serial No. 721,611.

To all whom it may concern:

Be it known that I, LEWIN A. MISKELL, a citizen of the United States, residing at Nelsonville, in the county of Athens and State of Ohio, have invented certain new and useful Improvements in Seats, of which the following is a specification, reference being had therein to the accompanying drawing.

10 This invention relates to a seat which is intended to be used in connection with a wash tub so that the ordinary tub may be used as a bath tub.

The principal object of the invention is 15 to provide an improved means for connecting the seat with the side of the tub so that the seat may be either suspended from the edge of the tub by means of an improved type of hook, or may be supported by a 20 spring clip carried upon the lower face of the seat.

This invention is illustrated in the accompanying drawings, wherein:—

Figure 1 is a perspective view of the seat 25 looking at the lower face. Fig. 2 is a sectional view through the side of the tub showing the seat suspended by the hooks. Fig. 3 is a view similar to Fig. 2 showing the seat supported upon the edge of the tub 30 by the resilient clip.

Referring to the accompanying drawings it will be seen that the seat comprises an arcuate body portion 10 which may be formed of any suitable material such as 35 wood. This body portion is provided with the curved edge so that it will fit into a tub as clearly shown in Fig. 2 with the curved edge resting against the side of the tub.

A pair of plates 11 and 12 are secured to 40 the lower face of the seat by means of the screws 13, and each is provided with a hinge ear 14 through which a pin 15 passes. A hook is pivotally connected with each of the plates 11 and 12 and has its end portion 16 45 terminating in the hinge ears 17 through which the pin 15 passes thus pivotally mounting the hook. The intermediate portion 18 of the hook extends at an angle to the end portion 16 so that when the hooks 50 are turned as shown in Fig. 1 the upper portions will converge and fit closely against the curved side of the body portion. The upper end portion 19 of each hook is bent as shown in Fig. 1 and extends toward the center of the body portion so that the upper edge of the hook is parallel with the upper

face of the body portion thus causing the two hooks to lie flat upon the upper edge of the tub 20 as clearly shown in Fig. 2. From an inspection of Fig. 2 it will also be seen 30 that these hooks tightly grip the upper edge of the tub so that there is no danger of the hooks working loose.

A resilient clip is secured to the lower face of the body portion and is formed from 35 a blank of spring metal doubled intermediate its length and then having its arms bent back upon themselves to form the two plates 21 and 22 which are positioned in spaced relation. It should be noted, however, that 40 these arms are close enough together so that when the seat is placed as shown in Fig. 3 the two plates will be spread apart a certain amount thus causing them to grip the sides of the tub and thus hold the seat in place. 45 The end portions of the blank are bent in opposite directions to form the feet 23 and 24 through which securing screws 25 are passed to securely attach the clip to the seat. When the seat is supported as shown in Fig. 50 3 the hooks will extend outwardly as shown in Fig. 3 and will thus form supports so that a cake of soap may be supported between the hooks and the lower face of the seat. The cake of soap will, therefore, not have to 55 be left floating in the water where it will be melted and wasted but will be held in a receptacle where it may be conveniently reached when it is desired to use it. It is, of course, obvious that the hooks will also be 60 formed of spring metal so that they will grip the cake of soap and prevent it from slipping loose. A seat has, therefore, been provided which may be suspended within 65 the tub from the upper edge by means of the hooks, or may be supported upon the upper edge of the tub by means of the spring clip, the hooks constituting a device for supporting a cake of soap.

Having thus described the invention, what 70 is claimed as new, is:—

1. A seat comprising a body portion, a supporting clip secured to the lower face of said body portion and formed from a strip of resilient metal doubled intermediate its 75 length and having its arms bent back upon themselves to form resilient plates, the end portions of the blank being bent in opposite directions to form feet, securing means passing through said feet and into said body 80 portion to hold said clip in place, hinge ears 85 carried by said body portion, and resilient 90

strips pivotally connected with said hinge ears and bent intermediate their length at an angle to their pivotally connected ends, the free ends of said strips being bent back upon themselves at an angle whereby said seat may be suspended from the upper edge of a tub by the hooked ends of said strips and supported upon the upper edge of a tub by said clip with said strips extending outwardly beneath said seat.

2. A seat comprising a body portion, means for removably connecting said seat with the upper edge of a tub, and resilient strips carried by said seat and being bent to form hooks extending beneath the seat in spaced relation thereto and forming an article receiving pocket.

3. In a seat of the character described a body portion, plates secured to said body

portion and carrying hinge ears, strips each having one end portion provided with hinge ears, a pin pivotally connecting the hinge ears of said strip with the hinge ear of said plate, said strip being bent at an angle intermediate its length whereby said strip will fit close against the bottom and side edge of said body portion with its upper end portions converging, and the upper end of said strip being bent at an angle to form hooks having their upper edges extending parallel to the upper edge of said body portion.

In testimony whereof I hereunto affix my signature in presence of two witnesses.

LEWIN A. MISKELL.
